UNITED STATES PATENT OFFICE.

DAVID G. WILLIAMS, OF YORK, PENNSYLVANIA.

IMPROVEMENT IN BALANCE-WHEELS FOR SEWING-MACHINES.

Specification forming part of Letters Patent No. 140,982, dated July 15, 1873; application filed June 7, 1873.

To all whom it may concern:

Be it known that I, DAVID G. WILLIAMS, of York, in the county of York and State of Pennsylvania, have invented a new and valuable Improvement in Sewing-Machines; and I do hereby declare that the following is a full, clear, and exact description of the construction and operation of the same, reference being had to the annexed drawings making a part of this specification and to the letters and figures of reference marked thereon.

Figures 1 and 2 of the drawings are representations of top views of my invention. Fig. 3 is a sectional view of the same. Figs. 4 and 5 are detail views.

My invention relates to forward motions on sewing-machines; and it consists of a loose fly-wheel on a sewing-machine shaft with such ratchet connection that the said fly-wheel may be coupled to the shaft only for forward motion, but will at all times turn loosely when the motion is reversed; also, a stopping-lever, which throws the ratchet out of connection so that the fly-wheel may be revolved either way without effecting the shaft. The object of my invention is to avoid a backward movement of the sewing-machine shaft and all the connected parts, and to provide an independent forward movement of the fly-wheel for the purpose of winding the bobbins of the sewing-machine.

In the drawings, A represents the shaft of a sewing-machine, which is a plain straight rod, and which has a journal-bearing, *a*, in the sewing-machine. The end of the said shaft projects beyond the said journal-bearing, and is there provided with a sleeve, B, which is fastened to it by a set-screw, *b*. A fly-wheel, C, is fitted to the said sleeve so as to turn freely on it. The fly-wheel may be of any ordinary construction to suit the purpose of applying my improvement. The one represented in the drawing has a driving-pulley, D, connected with it. The fly-wheel C is provided with a recess or chamber, E, to the bottom of which a pawl, F, is fastened by a pivot, *e*, and which is closed by a lid, G, with the aid of set-screws *g*. The hub *c* of the fly-wheel C is

longitudinally secured between the bearing *a* and the ratchet-wheel H, which is fastened to the end face of the shaft A by a set-screw, *h*. The facial bearing of the sleeve B against the sewing-machine bearing *a* and the facial bearing of the crank-plate at the other end of the shaft A insure steadiness of the said shaft A in a longitudinal direction. The shaft A cannot be constructed otherwise than straight to suit the construction of the sewing-machine; hence the sleeve B is preferable to a step or collar. The pawl F is provided with a one-sided tooth, *f*, which locks the ratchet-wheel H with the pawl with the forward motion, and slides over the ratchet-wheel with the back motion, and is caused to bear against the ratchet-wheel by a spring, *f'*, fastened to the back of it.

If a loose right-and-left motion of the fly-wheel is desired the pawl F is moved out of gear with the ratchet-wheel H by turning a key, I, in its fixed bearings *e'* on the fly-wheel, and the lid G so that its wing *i* enters the notch *i'* in the pawl F, and lifts the same until after passing the dead-lever it comes in contact with the nose *i''*, which serves to lock it. This latter arrangement is intended for the winding of bobbins, and serves to avoid the wearing and noise of the ratchets while the sewing machinery is standing still.

Fig. 2 shows a bobbin-winder, J, operated by the fly-wheel, the ratchet connection being suspended by the key I.

What I claim as new, and desire to secure by Letters Patent, is—

The combination, with the shaft of a sewing-machine and a loose fly-wheel thereon, of a ratchet-connection, operating in one direction only, and a key-tumbler for disengaging said ratchet connection when desired, as specified.

In testimony that I claim the above I have hereunto subscribed my name in the presence of two witnesses.

DAVID G. WILLIAMS.
